NELSON WHITE AND CHARLES G. TIEFEL, OF ROCHESTER, NEW YORK, ASSIGNEES TO
TODD PROTECTOGRAPH COMPANY, INC., OF ROCHESTER, NEW YORK, A CORPORATION OF NEW YORK.

CHECKWRITER.

1,329,449.

Specification of Letters Patent.

Patented Feb. 3, 1920.

Application filed July 10, 1918. Serial No. 244,246.

To all whom it may concern:

Be it known that we, NELSON WHITE and CHARLES G. TIEFEL, citizens of the United States of America, and residents of the city 5 of Rochester, in the county of Monroe and State of New York, have invented certain new and useful Improvements in Checkwriters; and we hereby declare the following to be a full, clear, and exact description of 10 the same.

While the invention is capable of application to a wide range of printing devices of various kinds, it is peculiarly applicable to machines of the kind known as check writers or check protectors for printing on checks and other documents, words or characters representing amounts to prevent "raising" or altering to make the papers appear to have a greater value than originally intended.

Many business concerns have come to use large check blanks known as voucher checks and still others have their checks printed in sheets, each sheet containing a number of 5 check blanks. It is desirable in using check-writing and protecting machines to be able to print or emboss the amount at any point on such voucher checks or upon the different checks in a sheet without first tearing the 10 checks apart.

Attempts have been made in the past to produce machines capable of printing on large voucher checks or sheets of checks, but, in doing this, the work supporting beds of the machines have simply been made larger. This has resulted in making the machines large and cumbersome, whereas one of the most desirable features such machines can have is to be small and compact.

The object of this invention is to provide means whereby small, compact machines of the kind mentioned may be so constructed as to permit using them to print at any point on even a very large sheet of paper.

With this and incidental objects in view, the invention consists in the novel construction and arrangement of parts, the essential elements of which are set forth in appended claims and a preferred embodiment of which is hereinafter described with reference to the drawings accompanying and forming a part of this specification.

In said drawings:

Figure 1 is a right side view of an illustrative machine with the invention applied thereto.

Fig. 2 is a detail with parts broken away and others in section to show features of the invention.

Fig. 3 is a longitudinal section through 60 the illustrative machine.

Fig. 4 is a section on the line 4—4 of Fig. 2 looking in the direction of the arrows.

Stated in a general way, the invention provides means whereby a sheet of paper 65 to be printed upon may easily be rolled up in the machine by the act of inserting the paper so that an impression can be made by a printing couple upon any part of the sheet. The machine to which the invention is shown 70 applied in the drawings is a very simple one and is intended only to illustrate how the invention may be applied generally to checkwriting and protecting machines. As will be more clearly apparent later on, the 75 exact form of the printing couple and mechanism for operating it is not essential to the invention.

The illustrative machine has an outside casing 10 supporting and inclosing the mechanism. Rotatably mounted in this casing is a shaft 11 having fastened thereto a type drum 12 upon the periphery of which are lines of type 13 for printing various legends. Fastened to the right hand end of the shaft 85 11 is a knob 14 by means of which the type drum may be turned to position any one of the type lines 13 above a platen or impression member 15. Rigid with the knob 14 is a dial or indicator 16 which serves in connection with an index 17 to guide the operator in setting the type drum.

The impression member or platen 15 is supported at its ends by arms 21 journaled on a rod 22. Engaging the underside of the 95 platen 15 are balls 23 loosely supported in a cross bar 24 supported at its ends by arms 25 of a platen operating lever pivoted on a rod 26. Only one of the arms 25 is shown in full in Fig. 3, the other being broken 100 away, but it will be clear that there is one of these arms at either side of the machine and that they branch from a common arm 27 extending toward the rear of the machine.

Springs 28 maintain engagement between the platen 15 and balls 23 and serve particularly to draw the platen down to the position shown after a printing impression has been taken.

Pivoted to the rear end of the arm 27 of the platen operating lever is one end of a link 31. The other end of the link 31 is pivoted to an arm 32 integral with an operating lever 33 and extending through a slot 34 in the rear of the casing. The operating lever 33 is pivoted at 35 between lugs 36 on the casing. It is clear that if the lever 33 is pressed down the arm 32 and link 31 will 10 act as a toggle to depress the rear end of the platen operating lever, thereby swinging the bar 24 and platen 15 upward against the tension of springs 37 to engage the platen 15 with the positioned type line 13. It is 15 also clear that the toggle movement referred to provides a means whereby a very heavy impression can be made by the platen co-acting with the type. This construction is 20 particularly desirable in case the machine 25 should be provided with the type and platen construction shown and described in United States Letters Patent No. 793,249, issued June 27, 1905 to L. M. Todd.

Ink is supplied by a roller 41 carried between the side arms of a spring tensioned yoke 42 carried by a removable plate 43 normally fastened to the top of the machine casing. Rotation of the type drum 12 to select type will cause the type to take from the roller 41 whatever ink they require for printing.

In order to receive and guide the work between the printing couple, that is, between the type drum 12 and the platen 15, the casing may be slotted as shown at 44. The sides of the casing are provided with circular openings 45 providing a tubular clearance across the machine and the work receiving slot 44 enters these circular openings 45 in an approximately tangential direction.

It is clear that, as so far described, if a sheet of paper is thrust into the machine through the slot 44, the tangential relation of the slot and circular openings 45 will 50 cause the paper to roll up automatically in said openings and that, with a reasonable amount of care, quite a wide sheet might be inserted in this way and adjusted laterally of the machine so as to be printed on at any 55 desired point. An indicator 46 on the casing serves to guide the operator in placing the paper to have the printing come on the proper line and a similar indicator (not shown) on the front of the machine serves 60 to indicate the correct lateral adjustment of the paper. A shield 47 extending across the machine is shaped to conform to the outline of the openings 45 and serves to prevent the paper from striking the type 13 in case the 65 paper should happen to buckle.

While the construction as described so far would be satisfactory within certain limits, means have been provided to make possible the use of larger sheets by relieving friction between the paper and the edges of the circular openings 45 and at the same time affording a certain accommodation to the gradually increasing size of the roll of paper in case the paper should be given several turns in winding. 75

This means comprises a number of anti-friction rollers 51 having their peripheries extending into the circular openings 45 far enough to be engaged by the work when the work is pushed in through the slot 44. The 80 rollers 51 are loosely supported on studs 52 on circular plates 53 on the sides of the machine. As shown in Fig. 2, the portions of the studs forming bearings for the rollers 51 are enough smaller than the openings 85 through the rollers to allow the rollers to have play radially on the studs and the heads of the studs are large enough to prevent the rollers from being laterally displaced. 90

Inclosing the studs and rollers is a finishing shield or cap 54. This cap 54 has formed on it ears 55 and the roller supporting plate 53 has similar ears 56. The two sets of ears are so positioned that when 95 the parts are in proper relation, screw holes through the two pairs of ears will coincide and provide a convenient means for attaching the devices to a machine. Both the cap 54 and the plate 53 are slotted as at 57 in 100 alignment with slot 44 so as to provide an entrance or clearance through which the work may be inserted.

The addition of the rollers 51 provides a means whereby the frictional resistance to 105 the movement of the work is minimized and even with a paper which is not very stiff, the simple act of thrusting the paper through the slot 44 will cause quite a large sheet to be rolled up automatically in the machine. If 110 the paper makes several turns, the rollers 51 are free to move radially on their supporting studs 52 to compensate for the increase in size of the roll and thereby offset, to a certain extent, any tendency the paper may 115 have to pinch and bind as it is being rolled up.

While the form of mechanism herein shown and described is admirably adapted to fulfil the objects primarily stated, it is 120 to be understood that it is not intended to confine the invention to the one form of embodiment shown and described for it is susceptible of embodiment in various forms, all coming within the scope of the claims 12 which follow.

What is claimed is:

1. In a machine of the class described, the combination with a printing couple, of a housing therefor having circular work re- 13

ceiving openings in its sides and work receiving slots tangentially entering said openings and elements rotatably mounted with their peripheries extending into said circular openings.

2. In a machine of the class described, the combination with a printing couple, of a housing therefor having circular work receiving openings in its sides and work receiving slots tangentially entering said openings and anti-friction rollers rotatably supported with their peripheries extending into said circular openings.

3. In a machine of the class described, the combination with a printing couple, of a housing therefor having circular work receiving openings in its sides to form a work receiving clearance across the machine and a work receiving slot tangentially entering said clearance, plates surrounding said circular openings, studs attached to said plates and antifriction rollers mounted for rotation and movement axially on said studs, the peripheries of said rollers extending 25 into the circular openings to be engaged by work pushed through the slot into the clearance.

4. In a machine of the class described, the combination with the members of a printing couple, of elements adjacent the print-

ing couple constructed to outline a tubular receptacle to receive the work when fed past the printing couple, and a plurality of loosely mounted elements extending into the interior of said receptacle to form an anti-friction 35 surface for coöperating with the work.

5. In a machine of the class described, the combination with the members of a printing couple, of elements adjacent the printing couple constructed to outline a tubular receptacle to receive the work when the work is pushed past the printing couple and loosely mounted rollers with their peripheries extending into the interior of the receptacle to form an anti-friction surface to be engaged 45 by the work.

6. In a machine of the class described, the combination with the members of a printing couple, of a guide constructed to direct the work between the members of said couple, circular openings into which the work may be pushed through the guide, the work entering said openings at a tangent to the circumferences of the openings and a plurality of loosely mounted elements extending into said openings to form anti-friction surfaces.

NELSON WHITE.
CHARLES G. TIEFEL.
